LACE

Bert Edson, East Providence, R. I., assignor to North American Lace Co., Inc., Philadelphia, Pa.

Application August 29, 1956, Serial No. 42,772

Term of patent 3½ years

(Cl. D47—6)

The figure on the drawing is a plan view of a lace showing my new design on a dark background so as to bring out more clearly the details thereof, a unit of which is repeated lengthwise between the selvage edges of the fabric as shown.

I claim:

The ornamental design for a lace, substantially as shown and described.
